CONNECTER FOR ELECTRIC CABLES

Edmund M. Livingston, Chambersburg, Pa.

Application October 24, 1932, Serial No. 639,213

6 Claims. (Cl. 173—328)

My invention relates generally to connectors for joining together electric cable sections, and more particularly to connectors which join a plurality of conductors of one cable section to a like number of conductors of another cable section, and which are so designed as to be capable of being assembled and disassembled with ease and rapidity.

While the invention is adapted for a variety of uses, I have found it to be especially useful as applied to the operation of electric tools on railway track. For example, in conducting welding and grinding operations along a section of railway track, it is desirable to employ comparatively long cables. It is a difficult matter to drag such cables along the ground following the operations as they continue from one point along the track to another. The cables are heavy and dragging them along the ground wears them out very quickly. By dividing the cables into comparatively short lengths and joining the sections together by the connectors of this invention, these difficulties are avoided.

The object of the invention is to provide a cable connector which is suited for such use as that described, as well as many other uses, and which is characterized by such features as interchangeability, the parts of the cable connector being duplicated at each end, and ease of assembly and disassembly.

Other objects and advantages characterizing my invention, including maintenance of good electrical contact between the cable sections which are joined together, will become more fully apparent from the description hereinafter set forth, of one embodiment or example of the practice of the invention. The description has reference to the accompanying drawing, whereof:

Fig. I represents a side elevation of a cable connector of my invention.

Fig. II represents an enlarged view of the same, partly in longitudinal cross section as indicated by the lines II—II of Fig. I, and partly in elevation.

Fig. III represents a transverse cross section of the same, taken as indicated by the lines III—III of Fig. II.

Fig. IV represents an additional transverse cross section of the same, taken as indicated by the lines IV—IV of Fig. II.

Fig. V represents a perspective view of one of the coupling members of the connector and the cap associated therewith.

Fig. VI represents a perspective view of one of the insulating bushings of the connector and the connecting plugs associated therewith.

Fig. VII represents a perspective view of a terminal member of one of the cable conductors; and,

Fig. VIII represents a perspective view of the connecting sleeve by which the coupling members are joined to each other.

In the drawing, I have shown an example of the use of my invention as applied to the joining together of electric cables carrying a pair of conductors. It will be obvious, however, that the connector of my invention is also applicable to cables carrying three or more conductors. Adjoining cable sections are designated at 1, and the conductors embedded therein are designated at 2. The connector used for securing together the adjoining cable sections comprises generally cylindrical bushings 3 housed within coupling members 4 and a connecting sleeve 5 of tubular form.

Each coupling member 4 has a threaded end 6 into which is fitted a correspondingly threaded cap 7, these parts being separately illustrated in Fig. V. The cap 7 preferably has a knurled flange 8 whereby it may be conveniently screwed into the coupling member 4. Each cap 7 terminates in a reduced portion 9 having an opening 10 through which the cable section 1 passes. Adjacent to the opening 10 there is an annular recess 11 which is adapted to be engaged by clamp members 12. While a variety of forms of clamp members may be utilized for the purpose of maintaining the cap 7 against rotation about the cable section 1, I have shown in the present instance, in Figs. I and II, clamp members having opposed jaws 13 fitting the annular recess 11 aforesaid and having part cylindrical portions 14 surrounding the cable and joined together by screw bolts 15 and nuts 16.

Each bushing 3, as shown in Fig. VI, is of substantially cylindrical contour and has therein a pair of spaced bores 20, each accommodating a terminal member 21. The bushings 3 are made of fibrous or other insulating material, and the terminal members 21 are maintained in place by set screws 22 engaging in annular recesses. The terminal members 21, one of which is shown in perspective in Fig. VII, are formed at their outer end with sockets 23 which accommodate the ends 24 of the conductors 2. To insure good electrical contact, the conductor ends 24 are by preference inserted within the sockets 23 and there secured by pouring solder into the annular cavity surrounding the conductor ends 24. At their opposite ends the terminal members 21 are provided with similarly shaped sockets 25, the latter sockets, however, being longitudinally slotted as indicated at 26 so as to resist yieldingly the

insertion therein of the connecting plugs 27. Each bushing has a keyway 28 in its exterior surface which engages the inner end of a pin 29 on the corresponding coupling member 4. The pins 29 are located near the adjoining ends of the coupling members 4 and when the connector is assembled they are diametrically opposite to each other.

It will be observed that the two bushings 3 are counterparts of each other, and present at the center of the connector opposed flat faces 30 with their sockets 25 in aligned position, when the connector is assembled. For joining the terminals 21 of one bushing 3 to those of the other bushing, the connecting plugs 27 are provided. The plugs 27 have like formed ends, and a cylindrical body portion 33 which is adapted to fit within the cavities 34 at the ends of the sockets 25. Inasmuch as the bushings 3 are alike and the connecting plugs 27 have like formed ends, no particular care need be exercised in choosing the proper end of one cable section which is to be joined to another, for the parts are interchangeable.

25 The coupling members 4 are likewise counter-parts of each other, and the outer ends of their pins 29 serve as the means by which one member may be coupled to the other. To effect this coupling I prefer to form the connecting sleeves 5 with diagonal slots 35 near their ends into which the outer ends of the pins 29 are adapted to be inserted. Each slot 35, as shown in Fig. VIII, has associated therewith a longitudinally directed opening 36 into which a pin 29 is guided and a slightly enlarged circular cavity 37 in which the pin is caught when the connector is assembled. Additional narrow slots 38 cause the outer tongues 39 of the connecting sleeve 5 to spring when the connecting sleeve is turned in assembling or disassembling the parts.

To assemble the parts together, it being assumed that the bushings 3 are within their respective coupling members 4, the connecting plugs 27 are inserted within the sockets 25 at the end face 30 of one of the bushings 3 and the connecting sleeve 5 is placed on one of the coupling members 4 and is adjusted so that the pin 29 lies within the longitudinal opening 36 at the end of the sleeve. The other coupling member 4 is then turned so that its pin 29 is diametrically opposite to the pin of the first coupling member, and is directed into the opening 36 of the slot at the other end of the sleeve 5. As the coupling members are pressed together, the connecting plugs 27 will seat themselves in the sockets 25, and the end faces 30 of the bushings 3 will come together. By a turning movement of the connecting sleeve 5, the pins are caused to be advanced diagonally through the slots 35 and into their circular cavities 37. Incident to this movement, the tongues 39 will yield somewhat, causing the pins to snap into the circular cavities 37 of the slots 36 and to be there retained against dislodgment.

65 Inasmuch as the cable sections 1 are clamped by means of the clamp members 12 to the coupling members 4, and the bushings 3 are keyed to the same members, it is impossible for the conductors 2 to become twisted within the connector. Moreover, the clamp members 12 serve additionally to relieve strain on the cable sections. When two or more cable sections are connected together and a force is applied tending to separate the elements of the connector, such as when the cable sections are dragged along the

ground, the connecting sleeve 5 maintains the parts in firm engagement, and there is no strain upon the conductors 2 where they join the terminal members 21.

80 From the above description it will be apparent that the connector of my invention may be assembled and disassembled with ease and rapidity and that it is so designed as to relieve the conductors of any tension or twisting strains. Furthermore, the sections of the connector are interchangeable, as contrasted with male and female couplings, so that either end of one cable section may be connected with either end of another section. The interchangeability of the ends of the connector and the manner in which the coupling is effected make it particularly useful as a temporary connection between adjoining cable sections.

85 While I have described one particular form which the connector of my invention may take, it will be apparent that various changes may be made in the form of the apparatus herein described and illustrated without departing from the spirit of my invention as defined in the annexed claims.

90 Having thus described my invention, I claim:

95 1. A connector for electric cable sections composed of a plurality of conductors comprising a pair of coupling members, each coupling member being clamped to the end of a cable section, bushings of insulating material housed within said coupling members, a plurality of sockets in the end face of each said bushing, said sockets forming the terminals of the conductors of said cable sections, detachable connecting plugs having like ends joining the sockets of one bushing with those of the other, and a connecting sleeve having like ends interfitting with the exterior surfaces of said coupling members and adapted upon rotation to draw one coupling member towards the other and to maintain said bushings in alignment with their end faces contiguous to each other.

100 2. A connector for electric cable sections composed of a plurality of conductors comprising a pair of cylindrical coupling members, each coupling member being clamped to the end of a cable section, bushings of insulating material fitting within and keyed to said coupling members, a plurality of sockets in the end face of each said bushing, said sockets forming the terminals of the conductors of said cable sections, detachable connecting plugs having like ends joining the sockets of one bushing with those of the other, and a connecting sleeve having like ends interfitting with the exterior surfaces of said coupling members and adapted upon rotation to draw one coupling member towards the other and to maintain said bushings in alignment with their end faces contiguous to each other.

105 3. A connector for electric cable sections composed of a plurality of conductors comprising a pair of cylindrical coupling members, each coupling member having an exterior projection near one end and being clamped at its opposite end to a cable section, bushings of insulating material housed within said coupling members, a plurality of sockets in the end face of each said bushing, said sockets forming the terminals of the conductors of said cable sections, detachable connecting plugs having like ends joining the sockets of one bushing with those of the other, and a connecting sleeve having like slotted ends engaging the exterior projections of said coupling members, and thereby adapted upon rotation to draw one coupling member towards the other and serv-

ing to maintain said bushings in alignment with their end faces contiguous to each other.

4. A connector of electric cable sections composed of a plurality of conductors comprising a pair of cylindrical coupling members, each coupling member having an exterior projection near one end and having a threaded cap at its other end, each said cap having an opening for the passage of a cable section therethrough and having an annular flange adjacent to said opening, clamps engaging the cable sections and the annular flanges of said caps, bushings of insulating material keyed within said coupling members, a plurality of sockets in the end face of each said bushing, said sockets forming the terminals of the conductors of said cable sections, detachable connecting plugs having like ends joining the sockets of one bushing with those of the other, and a connecting sleeve having like slotted ends engaging the exterior projections of said coupling members and joining one coupling member with the other.

10 5. A connector for electric cable sections composed of a plurality of conductors comprising a pair of cylindrical coupling members, each coupling member having a pin passed through its wall, and each coupling member being clamped to a cable section, bushings of insulating material housed within said coupling members and

having keyways engaging the inner ends of said pins, a plurality of sockets in the end face of each said bushing, said sockets forming the terminals of the conductors of said cable sections, detachable connecting plugs having like ends joining the sockets of one bushing with those of the other, and a connecting sleeve having like slotted ends engaging the outer ends of said pins, thereby joining one coupling member with the other.

6. A connector for electric cable sections composed of a plurality of conductors comprising a pair of cylindrical coupling members, each coupling member having a pin passing through its wall, and each coupling member being clamped to a cable section, bushings of insulating material housed within said coupling members and having keyways engaging the inner ends of said pins, a plurality of sockets in the end face of each said bushing, said sockets forming the terminals of the conductors of said cable sections, detachable connecting plugs having like ends joining the sockets of one bushing with those of the other, and a connecting sleeve having like diagonally slotted ends engaging the outer ends of said pins and adapted upon rotation to draw the coupling members and bushings together.
